UNITED STATES PATENT OFFICE.

JOHN FRANK STREBERGER, OF DETROIT, MICHIGAN, ASSIGNOR TO JOSEPH N. SMITH & COMPANY, OF DETROIT, MICHIGAN, A CORPORATION OF MICHIGAN.

COMBINED STRIKER AND BUMPER FOR DOORS.

1,196,171.

Specification of Letters Patent. Patented Aug. 29, 1916.

Application filed April 2, 1915. Serial No. 18,640.

To all whom it may concern:

Be it known that I, JOHN FRANK STREBERGER, a citizen of the United States, residing at Detroit, county of Wayne, State 5 of Michigan, have invented a certain new and useful Improvement in Combined Strikers and Bumpers for Doors, and declare the following to be a full, clear, and exact description of the same, such as will 10 enable others skilled in the art to which it pertains to make and use the same, reference being had to the accompanying drawings, which form a part of this specification.

This invention relates to a combined 15 striker and bumper for doors, more particularly adapted for use with automobile doors, and an object of the invention is a simple and inexpensive device which may be applied as a unit to the door-jamb so arranged 20 as to absorb shock incident to the shutting of the door and also adapted to hold the tongue of the door lock in engagement with its catch to prevent rattling thereof. These 25 objects and the novel features of construction are hereinafter more fully described and claimed as shown in the accompanying drawings in which—

Figure 1 is a perspective view of a striker and bumper plate embodying my invention. 30 Fig. 2 is a section taken through the striker plate and bumper showing the door and door-jamb in dotted lines.

Like characters of reference refer to like parts throughout the drawings and specification. 35

In the preferred form of the invention shown in the drawings, the striker plate 1 is provided with a usual curved tongue 2 adapted to engage the tongue of the door 40 lock upon the closing of the door to retract the same for engagement in the aperture 3 in the plate, as is usual in commonly known striker plates. The striker plate is also provided with an integrally formed bumper 45 plate 4 extending at an angle thereto to fit the angle between the door stop and frame. This bent portion 4 is apertured at 5 substantially parallel with the center line of the aperture 3, and projecting through this aperture is a plunger 6 adapted to engage 50 against the door when closed and to hold the tongue of the door lock against the edge of the aperture 3, as indicated in dotted lines in Fig. 2.

55 As indicated in Fig. 2, the plunger or

bumper 6 is preferably made hollow and is provided with an external circumferential flange 7 to prevent its being forced through the aperture 5. At the back of the bumper plate 4 is secured a plate 8 and this plate is 60 provided with a recess or pocket 9 into which the plunger may be forced on closing of the door. A spring 10 is positioned in the recess and extends into the hollow plunger 6 as shown tending to force the plunger 65 outward through the aperture 5. By making the plunger hollow a comparatively long coiled spring may be utilized without the necessity of providing a deep pocket therefor.

As will be noted in Fig. 2, the door-jamb 70 is provided with a flange preferably mortised to receive the bumper member 4 and plate 8. As this flange is of little thickness and strength, the bumper plate provides a 75 means to relieve the flange of shock upon closing of the door. The spring pressed plunger 6 also tends to ease the shock of closing the door and even though the plate 4 be struck in such operation the strain is absorbed by the striker plate and not transmitted to the said flange. The plunger also 80 holds the door with the tongue of the lock in engagement with the edge of the aperture 3 and prevents a rattling thereof.

The striker and bumper being formed as a 85 unit, as shown, less labor is involved in applying the device to a door-jamb than if separate instrumentalities were utilized as is usual. The device formed as shown, is also less expensive to manufacture.

Having thus briefly described my invention and its utility, what I claim and desire to secure by Letters Patent of the United States is—

1. A striker and bumper for doors comprising an apertured striker plate, a bumper plate extending at an angle thereto at the rear edge, said bumper plate having an aperture, a plate secured at the back of the bumper plate provided with a pocket covering the aperture, a plunger in the aperture, and a spring in the pocket engaging said plunger. 95

2. A striker and bumper plate for doors comprising an apertured striker plate, a bumper plate extending at an angle thereto at the rear edge, said bumper plate having an aperture, a spring sustaining member at the rear of the aperture, a plunger in said aperture, said plunger having a flange 100 105 110

greater in diameter than the aperture to prevent the plunger from passing therethrough, and a spring supported by the sustaining member and engaging the plunger.

- 5 3. A striker and bumper plate for doors comprising an apertured striker plate, a bumper plate extending at an angle thereto at the rear edge, said bumper plate having an aperture, a pocket provided at the rear 10 of the aperture, a hollow plunger extending through the said aperture, said plunger having a flange greater in diameter than the aperture to prevent the plunger from passing therethrough, and a spring in the said pocket extending into the hollow plunger.
- 15 4. A striker and bumper for doors com-

prising an apertured striker plate, a bumper plate extending at an angle thereto and provided with an aperture, a sustaining member at the rear of said aperture, and a yieldable member carried by the sustaining member, said yieldable member including a portion extending through the aperture in the bumper plate adapted to engage against the door when closed.

20 25 In testimony whereof, I sign this specification in the presence of two witnesses.

JOHN FRANK STREBERGER.
